UNITED STATES PATENT OFFICE.

DONALD S. MUNN, OF SOUTH EUCLID, OHIO, ASSIGNOR TO THE MCMLYER INTERSTATE COMPANY, OF BEDFORD, OHIO, A CORPORATION OF OHIO.

BOAT UNLOADER.

Application filed May 20, 1925. Serial No. 31,488.

This invention relates to a boat unloader and has for its object to provide an unloader adapted to be mounted upon the vessel being unloaded and to deliver the material onto a pile extending along the dock beside which the vessel is secured while being unloaded.

The unloader herein shown is particularly designed for unloading coal, ore, or other material that can be handled by means of a clam-shell bucket from the hold of a vessel and delivering the same in a pile along the dock beside which the vessel is placed, and consists of a carriage running upon tracks extending along opposite sides of the deck of the vessel and spanning the hatch, elevating mechanism on the carriage, and a piling conveyer to which the elevating mechanism delivers the material from the hold of the vessel, said conveyer comprising a vertically swinging conveyer carrying boom pivoted to the turntable and adjustable about its pivot to maintain the delivery end thereof at the proper height above the pile, the elevating mechanism and piling conveyer being both mounted upon a turntable on the carriage to permit sluing of the conveyer boom to position the discharge end thereof at the desired distance from the edge of the dock.

With the above and other objects in view, the invention may be said to comprise the apparatus illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this specification in which Fig. 1 is a side elevation of the unloader showing in transverse section a portion of the vessel upon which the unloader is mounted; Fig. 2 is a side elevation showing the superstructure carried by the turntable looking from the dock side, the hoisting mechanism and piler boom being omitted; Fig. 3 is a horizontal section showing the floor of the turntable and the mechanism mounted thereon; Fig. 4 is a plan view showing a portion of the dock and the vessel alongside of the dock with the unloader mounted thereon.

Referring to the accompanying drawings,

the vessel upon which the unloader is mounted, is indicated by the numeral 1, and this vessel is provided with a hold 2 and deck 3 provided with the hatch 4 which may extend the full length of the hold. The openings in the deck 3 through which the material is loaded and unloaded may consist of a row of spaced hatches or a single hatch extending the full length of the hold. The dock 5 alongside which the vessel is secured, is designed to receive a storage pile of the desired width and length, the material being delivered by the unloader directly from the hold of the vessel onto the storage pile on the dock. Extending along opposite sides of the deck of the vessel are track rails 6, upon which the carriage 7, which supports the unloader mechanism, travels. The carriage 7 consists of a rectangular frame 8 which is supported at each corner upon equalizing trucks 9 which carry flanged wheels which run upon the track 6. Any suitable means may be provided for traveling the carriage along the deck of the vessel. As shown herein the front and rear wheels of the carriage may be propelled in either direction by suitable electric motors mounted upon the frame 8. A turntable 11 is rotatably mounted upon the frame 8 of the carriage and is supported upon suitable rollers 12, provided in the circular raceway in which the turntable is mounted. The frame 8 of the carriage has an open central portion and the turntable 11 has platforms 13 and 14 along opposite sides, between which there is an opening 15 which is over the open central portion of the frame 8 and extends across the hatch 4 so that an unobstructed space is provided for the passage of the hoisting members to and from the hold of the vessel. A sluing rack 16 is secured to the carriage frame 8 concentric with the axis of rotation of the turntable, and provides means whereby the turntable may be adjusted to any desired angular position. Suitably controlled sluing motors 17 and 18 are mounted upon the platforms 13 and 14 and drive vertical shafts 19 and 20 which are journaled in the turntable and carry suitable pinions at their lower ends which mesh with the rack 16 on the carriage frame.

The turntable 11 carries a superstructure consisting of pairs of posts 21 secured to the turntable adjacent opposite sides thereof,

a connecting truss 22 connecting each pair of side posts and connecting beams 24 which extend between the bottom portions of the two connecting trusses 22. The connecting beams 23 serve to support spaced rails 24 which extend along the tops of the beams 23. The turntable 11 extends at one side beyond the superstructure and upon the projecting portion of the turntable there is mounted an operator's house 25 within which the hoist-operating mechanism is mounted. A second operator's house 26 may be provided upon one of the platforms within the superstructure. A trolley 27 is mounted to travel upon the rails 24 and suspended from this trolley is the grab-bucket 28, preferably a clam-shell bucket which is adapted to be lowered into the hold of the vessel to remove the material therefrom. The bucket 28 is suspended from the trolley 27 by means of a hoist cable and the bucket is raised and lowered, and opened and closed by means of hoist and hold drums upon which the cables are wound, the hoist and hold drums being mounted within the house 25 outside the superstructure, the hoist and hold drums 29 and 30 being operated by suitably controlled electric motors 31 and 32. The trolley 27 is shifted back and forth along the beams 23 by means of a shifter cable 33 which has its opposite ends wound in opposite directions upon a drum 34 mounted upon the platform 14, the drum 34 being operated in either direction by a suitably controlled electric motor 35. The two runs of the cable 33 extend from the drum 34 over a guide sheave 36 carried by one of the posts 21 and one run extends over a guide sheave 37 at one end of the beam 23 and the other run extends over a sheave 36 mounted on the post 21 directly above the sheave 36 and over guide sheave 38 at the opposite end of the beams 23, and is connected to the opposite end of the trolley 27. By rotating the drum 34 in the proper direction, the trolley 27 may be shifted in the desired direction along the beams 23. On the side of the turntable opposite the operator's house 25 there is a radially extending trussed boom 39 which is supported at its inner end on a bracket 40 carried by the turntable by means of a horizontal pivot pin 41. The boom 39 carries an endless belt conveyer 42 which runs over rollers 43 and 44 at the inner and outer ends of the boom, the conveyer 42 serving to receive the material delivered by the grab-bucket 28 and to deliver the same onto the pile on the dock. A suitable hoist cable 45 is connected to the outer end of the boom 39 and extends to a hoist drum 46 mounted upon the platform 13 of the turntable, the hoist-drum 46 being driven by a suitably controlled electric motor 47. By means of the hoist cable 45, the discharge end of the conveyer 42 may be

adjusted to and held at the desired height. To properly deliver the material discharged from the bucket 28 to the belt 42, a hopper 48 is mounted upon the inner end of the boom 39 and this hopper is provided with a suitable mechanical feed mechanism which feeds the material at the desired rate from the hopper 48 to the conveyer-belt 42. As herein shown, the hopper 48 is provided with a feed-belt 49, which extends across the bottom of the hopper and discharges onto the belt 42. The feed and conveyer mechanism on the boom is a power-driven unit separate from the mechanism on the turntable and any suitable drive mechanism may be provided on the boom. The boom 39 is mounted in alignment with the beams 23 upon which the bucket-supporting trolley 27 runs, and the beams 23 project outwardly from the superstructure over the hopper 48, so that a loaded bucket may be shifted to a position where it may dump its material into the hopper 48. The space between the posts 21 at the side of the turntable on which the boom 39 is mounted is unobstructed, so that the bucket 28 may pass from the interior of the superstructure to a position directly over the hopper 48.

In the operation of the unloader, the bucket 28 will be lowered into the hold of the vessel by rotating the hoist drum 29 in a direction to lower the bucket. When lowered into the mass of material within the hold, the winding up of the hoist-cable will cause the jaws of the bucket to close, and the loaded bucket will be elevated to a position within the superstructure immediately below the beams 23. The shifting drum 34 will then be operated to shift the trolley 27 outwardly to a position directly over the hopper 48, and the bucket will be dumped by operating the hold and hoist drums. The material within the hopper 48 is fed at a uniform rate to the conveyer-belt 42 by the feed-belt 49, and is discharged from the outer end of the boom upon the storage pile on the dock. The outer end of the boom 39 is preferably maintained a short distance above the pile to which the material is being discharged, and as the height of the pile increases the hoist-drum 46 may be operated to elevate the discharge end of the boom. By sluing the turntable the boom 39 may be disposed at any desired angle with respect to the edge of the dock so that the discharge end of the boom may be positioned at the desired distance from the edge of the dock.

Having described my invention, I claim:

1. The combination with a vessel, of a carriage mounted on the deck of said vessel, said carriage spanning the hatch of the vessel and being movable longitudinally of the vessel, a turntable mounted on said carriage and having an opening adapted to be

positioned over the hatch, said carriage and turntable having open central portions, an outwardly extending boom secured at its inner end to the turntable, a conveyor on 5 the boom, a feed hopper supported above the inner end of the conveyor, a superstructure carried by the turntable, a track carried by the superstructure over the open central portion of the turntable and carriage 10 and projecting over said hopper, a trolley on said track, means for shifting the trolley on the track from a position over the open central portion of the turntable to a position over said hopper, a hoisting member 15 suspended from the trolley, means for raising and lowering said member through the opening in the turntable and for discharging the same into the hopper, and means for adjusting said boom and turntable.

2. The combination with a vessel, of a carriage mounted on the deck of the vessel for movement longitudinally thereof, said carriage spanning the hatch of the vessel, a turntable mounted on said carriage and having 25 an opening adapted to be positioned over the hatch, said carriage and turntable

having open central portions over the hatch, a superstructure on the turntable, a transverse track mounted on the superstructure over the open central portions of the carriage and turntable, said track projecting beyond one side of the superstructure, a trolley movable on the boom from a position over the open central portion of the turntable to a position outside said superstructure, a vertically swinging boom pivoted to the turntable beneath the projecting end of the track, an endless conveyor on the boom, a feed hopper between the track and boom, a grab bucket suspended from the trolley, means for raising and lowering the grab bucket through the turntable and for opening and closing the same, and mechanism mounted on the turntable for shifting the trolley on the track, from a position over the open central portion of the turntable to a position over said feed hopper for shifting the turntable about its axis and for raising and lowering the outer end 50 of the boom.

In testimony whereof, I hereunto affix my signature.

DONALD S. MUNN.
